(57) **CLAIM**

I claim the ornamental design for the adhesive insert stud, as shown and described.

DESCRIPTION

FIG. 1 is a side view of an adhesive insert stud, the opposite side being a mirror image thereof;

FIG. 2 is a front view of the adhesive insert stud, the back view being a mirror image thereof;

FIG. 3 is a top view of the adhesive insert stud; and,

FIG. 4 is a bottom view of the adhesive insert stud.
